PANE RETAINER

Jacob I. Russakov, Chicago, Ill.

Original application March 25, 1933, Serial No. 662,665, now Patent No. 1,990,755. Divided and this application June 13, 1934, Serial No. 730,438.

3 Claims. (Cl. 220—82)

This invention relates to improved means for retaining a pane of glass or similar light-transmitting panel in a frame. It is of particular utility in connection with display closures for cans or boxes from which goods such as crackers, biscuits, and similar articles are dispensed in retail stores.

Display closures of this type generally include a fixed frame and a swinging lid hinged to the frame, the lid being also of frame construction and carrying a transparent glass pane. One of the objects of the present invention is to provide improved and peculiarly advantageous means for holding the pane in proper position while permitting its ready removability for any purpose, and means whereby such a pane may be readily inserted both initially and should the one in use become broken.

Pane-retaining means of this general type are shown for example in the patent to Russakov No. 1,511,426 and the patent to Campbell No. 1,656,816; but in these earlier constructions the spring retaining means must be either entirely separated from the frame, or must be freed at one end and swung at the other end entirely out of the plane of the frame so as to permit the glass to be inserted or removed, and this has been found objectionable since with the prior art devices the spring is frequently broken off, seriously bent out of shape, or otherwise lost, and in addition time and effort are consumed in loosening and adjusting the retainer.

An important object of the present invention is to provide a spring retaining member which is positively but yieldingly maintained in one of two selected positions, in one of which it is operative to engage the pane, and in the other of which it is in inoperative position so that the pane may be removed or inserted, the spring retaining member being desirably always in one or the other of the two closely-adjacent positions, and being flexed from one to the other by a relatively slight movement, thus effecting a saving in time and effort as well as guarding against loss or breakage of the spring.

This application is a division of my copending case Ser. No. 662,665, filed March 25, 1933 for "Display covers," which has issued as Patent No. 1,990,755, granted February 12, 1935.

In the drawing—

Figure 1 is a perspective view of a fragment of a conventional display closure of the type described, with the lid swung back to show its underside and with the pane retainer associated in

holding position with respect to the pane of glass;

Figure 2 is a vertical section through the lid and closure as a whole, with the lid closed and showing the pane retainer in elevation; and

Figure 3 is another bottom view of the lid in broken plan, showing the two pane retainers, one in holding position at one side of the lid and the other at the other side, in released position (in full lines) and in holding position (in dotted lines).

Referring in detail to the figures of the drawing, the box 10 is the usual article container open at one end for dispensing purposes, this end being covered in the usual way by the display closure 11. The display closure 11 includes the usual fixed frame 12 which slips over the open end of the container 10 and through the open center 12a of which access may be had to the articles in the container.

The closure 11 includes the swinging lid 13 which may be hinged to the fixed frame 12 by the hinge mechanism indicated generally by the numeral 14 and more specifically described and claimed in my copending application already referred to herein. As is well known, the lid 13 is adapted to close the opening 12a in the fixed frame member 12.

For display purposes, the lid 13 is also partially in the form of a frame having a flat portion 20 in which is the display opening 20 and having the side members 15, 16 and the front and rear members 17, 18 respectively, the rear member 18 forming a part of the hinge means 14. In this instance, the sides 15, 16 are substantially parallel and perpendicular to the flat portion.

The pane 19 of glass or the like is desirably of an area slightly less than the inner dimensions of the lid frame, so as to completely cover the central display opening 20 in the lid, through which the articles in the container 10 may be viewed when the lid is closed. In this instance, the pane 19 is shown as a substantially square piece of transparent glass of a thickness of between one-sixteenth and one-eighth of an inch, or thereabouts.

To retain the pane in tight contact with the inner surface or underside of the lid frame, I provide the improved pane retainers 21, there being as here shown a pair of these retainers, entirely separate one from the other and acting independently at opposite margins of the glass pane. These flexible resilient retainers hold the pane in a fixed plane relatively to the lid parallel with the flat portion and they are associated

with the lid frame, in this instance, by being mounted on the side frame members 15, 16 respectively. Since the retainers 21 are alike, a detail description of one will suffice for both.

5 The principal element of each of the pane retainers 21 is a spring retaining member formed desirably of a piece of strong round wire 22, here shown as of about the same thickness as the pane of glass 19.

10 In accordance with my present improvement, the wire 22 is permanently held at both ends by rivets 23 which pass through the side frame members of the lid and are headed on the inner and outer faces of the lid, the inner head 24 of each 15 rivet being spaced from the inner face of the frame member so that the wire 22 may be bent around the rivet as at 25 to form an eye which is permanently held between the frame and the head 24 of the rivet. Slight rotational movement of each eye on its respective rivet, however, 20 is permitted to accommodate the flexing of the wire as presently described.

15 Looking first at the lid in plan as shown in the lower half of Figure 3, the wire 22 extends toward the edge 29 of the side 15 parallel to the side and is bent intermediately of its ends to form a substantially straight but relatively short portion 26 which is offset outwardly of the lid and overlies the edge 29. In the vicinity of this offset 20 the lid is provided with a detent here shown as a lug 27 formed by slotting the side frame member 15 or 16, as the case may be, preferably arcuately as at 28, and striking inwardly the margins of this slot farthest removed from the 35 pane 19, so that the lug 27 is of somewhat semi-circular shape and has a substantially flat edge directed toward the glass, upon which edge the offset 26 may be caught, as shown in broken lines in the lower half of Figure 3 or in full lines in the upper half of Figure 3, in which position the 40 wire 22 is releasably maintained with its portions between the offset portion 26 and its ends out of parallel relation with the side 15 or 16 and overlying the flat portion.

45 In accordance with my invention, in one of the two alternative positions of the spring retaining member or wire 22, or in other words in the inoperative position of the spring retaining member, the main part of the wire is substantially 50 parallel with the side frame member 15 or 16, as the case may be, and snugly hugs this member to be out of the way of the glass. In other words, in one of its alternative positions the retainer while still secured at its ends is entirely outside 55 the perpendicular projection of the glass pane 19. To positively but yieldingly maintain the spring wire in this position, the wire is flexed so that the offset 26 engages and extends out over the edge 29 of the side frame member, as best shown 60 in full lines in the lower half of Figure 3, the offset 26 thus also being out of the way of the glass and serving to hold the spring in inoperative position. When both of the spring retaining members 22 are in this position, they are free of 65 the glass and the pane may be readily removed or replaced. The inherent resiliency of the wire, when flexed as described, maintains the offset 26 in engagement with the edges 29 so as to keep the wires out of the way while the glass is being 70 handled, and at the same time since the offset 26 is permitted to extend out over the frame in this position of the wire, the wire tends to straighten out parallel with the side of the frame and thus hold itself entirely clear of the margins of the 75 glass, leaving practically the entire inner area of

the frame occupied by the glass free of any obstruction to removal or insertion of a pane.

When the pane has been inserted, the wire 22 of each retainer is flexed in the opposite direction, again against its own resiliency, away from engagement with the edge 29 of the frame as shown in the lower half of Figure 3 and into the position shown in the upper half of Figure 3, in which the wire has been sprung around the detent 27 until the offset 26 is in engagement with the relatively flat edge of the detent facing the pane 19. Thereupon, the wire 22, by abutment of the offset 26 with the inner face of the frame, is caused to be bowed inwardly of the side frame member 15 or 16, as the case may be, to overlie the margin of 15 the glass 19 and retain the glass from falling out. The inherent resiliency of the wire again maintains it in this position until the wire is again flexed to releasing position as already described. 20

25 In order that the retaining means may not only hold the glass against falling out but may also hold it tightly but resiliently in contact with the inner face of the frame to guard against rattling or displacement of the glass which might 30 lead to breakage, the wire 22 is further bent in an oppositely directed plane at two places each intermediately of the offset 26 and the eyes 25. In this instance the wire is bent or offset as at 35 30, best shown in Figure 2, toward the inner face 30 or underside of the lid and thus toward the pane 19, so that two humps are produced in the wire which afford pressing points for the wire against the glass when the wire is placed under tension in holding position in engagement with the 35 detent 27.

40 Thus the wire of each of the retainers 21 may be readily and independently flexed from one alternative position to the other by a relatively slight movement while being retained in each position by the resiliency of the wire.

Having described my invention, what I claim as new and desire to secure by Letters Patent is:

1. In a pane retainer of the class described, 45 the combination with a frame member having a flat portion and substantially parallel sides perpendicular to said flat portion, of a transparent pane parallel with said flat portion but terminating short of the parallel sides, an elongated 50 springy wire member substantially permanently secured at each end on one of said parallel sides, said member being normally entirely outside the perpendicular projection of the pane, and means for releasably retaining the wire flexed intermediate its ends into position within said perpendicular projection of the pane and closely overlying the pane. 55

2. In a pane retainer of the class described, 60 the combination with a frame having a flat portion and a side substantially perpendicular thereto, of an elongated resilient flexible member permanently secured adjacent each of its ends to the frame, said member normally extending from each end toward an edge of the said side and 65 parallel to said side, said member having a portion intermediate its ends offset from said portions thereof which are parallel to said side, said offset portion overlying the said edge, and a detent on the frame for engaging said offset portion of the flexible member to maintain the flexible member releasably with its portions between its offset portion and its ends out of parallel relation with said side and overlying the flat portion. 70

3. In a pane retainer of the class described for use with a frame member having a flat portion and a side perpendicular to said flat portion, the combination of an elongated springy wire member permanently secured at each end on the said side, end portions of said member extending in one position from said secured ends bowed in a plane parallel and closely adjacent to the side, and said member having a medial offset portion, said medial offset portion being

adapted to hook over the edge of the side when the end portions of the member are bowed in a plane parallel with the side, and a lug on the inner face of the side adapted to be engaged by the medial offset portion to releasably retain the end portions of the member bowed in a plane transverse to the side and overlapping the flat portion in another position of the member. 5
